UNITED STATES PATENT OFFICE.

JACOB B. CONOVER, OF JERSEY CITY, NEW JERSEY.

CLAMPING AND LOCKING MEANS FOR MILK-CAN COVERS.

1,361,141.

Specification of Letters Patent.

Patented Dec. 7, 1920.

Application filed December 7, 1916. Serial No. 135,592.

To all whom it may concern:

Be it known that I, JACOB B. CONOVER, a citizen of the United States, residing at Jersey City, in the county of Hudson and State 5 of New Jersey, have invented certain new and useful Improvements in Clamping and Locking Means for Milk-Can Covers, of which the following is a specification, reference being had therein to the accompanying drawings, forming part thereof.

The objects of the invention are facility and economy of manufacture, and the production of a device which shall be rugged, durable, tight, reliable and conveniently 10 operated.

In the accompanying drawings:

Figures 1, 2 and 3 show one embodiment of the invention, and Figs. 4, 5 and 6 illustrate another construction in which the same 15 generic invention may be embodied.

Fig. 1 is a plan view of the neck and cover of a milk can showing the cover-clamping means at one side in section on the plane 1, 1, of Figs. 2 and 3, which is the horizontal 20 plane of the yoke pivots 4^b, the parts being represented in clamping positions.

Fig. 2 is a partly sectional front elevation of the upper end of the can shown in Fig. 1, the section plane being indicated at 2, 2, of 25 Fig. 1.

Fig. 3 is a partly sectional left elevation of the upper end of the can shown in Figs. 1 and 2, the section plane being indicated at 3, 3, of Figs. 1 and 2.

Fig. 4 is a plan view of the neck and cover of a milk can showing the cover-clamping means at one side in section on the plane 4, 4, of Figs. 5 and 6, which is the horizontal 30 plane of the yoke pivots 4^a, the parts being represented in clamping positions.

Fig. 5 is a partly sectional front elevation of the upper end of the can shown in Fig. 4, the section plane being indicated at 5, 5, of Fig. 4.

Fig. 6 is a partly sectional left elevation of the upper end of the can shown in Figs. 4 and 5, the section plane being indicated at 6, 6, of Figs. 4 and 5.

In the construction of Figs. 1, 2 and 3, the 45 can cover 8^b fits like a cap over the can neck 9^b. The cover is formed of sheet metal and recessed at its inside annular corner to receive a gasket 12^b which lies upon the edge of the can neck. The sheet-metal cylindrical rim of the cover is reinforced by a rela-

tively heavy outside ring 5^b perforated at diametrically opposite points to receive the pivotal studs 4^b projecting inwardly from the ends of the clamping-and-locking bail-shaped yoke 3^b. Projecting outwardly from the ends of the yoke or bail 3^b are oblong clamping bosses or cams 6^b whose centers lie in the projected axis of the pivot studs 4^b and whose major dimensions are normal to the plane of the bail, so that when the bail 60 is swung into the plane of the can mouth, the clamping cams will have their major radii (with respect to their pivotal axis) vertically disposed to engage the inward overhang of the clamping ears 7^b riveted on 65 the neck ring 9^b. The under sides of the overhang walls of these clamping ears are recessed to receive the beads 13^b formed along the shorter edges of the clamping cams, so that the seating of these beads in 70 said recesses will tend to resist lateral displacement of the ears. The vertical stop-ribs 14^b of the opposite clamping ears are disposed on opposite sides of the diametric line which is the pivotal axis of the yoke 75 when placed in clamping position, so that the can cover may be placed over the mouth of the can with its clamping bail or yoke in the vertical plane and then rotated about a vertical axis until the stop-ribs arrest the 80 clamping cams in position to effect their clamping engagement with the ears when the yoke is swung either way into the horizontal plane. A locking ear 11^b is riveted to the neck ring in position to arrest the 85 middle of the clamping yoke in the horizontal plane, and this ear and the yoke are prefabricated in register so that the yoke may be padlocked or conveniently tied to the ear.

In the construction shown in Figs. 4 to 95 6 inclusive, the clamping yoke 3^a is pivoted in internal enlargements 5^a formed in the inner annular corner of the cast cover 8^a whose cylindrical portion fits within the neck of the can and has an outer integral 100 flange against which the gasket 12^a is seated in position to effect a sealing engagement with the upper edge of the can neck. The clamping cams are semi-circular and engage the overhang of the clamping ears 7^a when 105 the clamping yoke is swung into the horizontal plane on one side of the cover, and are unclamped when the yoke is swung one hundred and eighty degrees into the same plane on the opposite side of the cover.

The invention may be embodied in still other specific constructions within the scope of the following claims:

1. Covering means for cans with cylindrical necks, comprising a cover with a cylindrical rim, a bail-shaped yoke spanning the cylindrical cover rim and pivoted thereto at diametrically opposite points, clamping ears secured to the can outside the cylindrical cover rim, and clamping devices on the yoke, said clamping ears and devices being adapted to coact for clamping the cover on the can when the yoke is swung toward horizontal position on one side of the cover.
2. Covering means for cans with cylindrical necks, comprising a cover with a cylindrical rim, clamping ears secured to opposite sides of the can in positions outside the cover rim, a bail-shaped yoke spanning the cover rim with its ends disposed between said rim and the opposite clamping ears and pivoted to said rim, and clamping devices on the ends of the yoke, said clamping devices and the clamping ears being adapted to clamp the cover in position when the yoke is swung toward horizontal position on one side of the cover.
3. Covering means for cans with cylindrical necks, comprising a cover with a cylindrical rim, clamping ears secured to opposite sides of the can neck in positions outside the cover rim, a yoke spanning the cover rim with inwardly projecting pivotal studs entering the rim and said yoke hav-

ing clamping devices projecting outward toward the clamping ears, said clamping devices and ears being designed to clamp the cover on the can neck when the yoke is swung toward horizontal position on one side of the cover.

4. Covering means for cans with cylindrical necks, comprising a cover with a cylindrical rim embracing the can neck, clamping ears secured to opposite sides of the can in positions outside the cover rim, a bail spanning the cover rim and pivoted thereto, and clamping devices on said bail, said clamping ears and clamping devices being designed and adapted to clamp the cover on the can neck when the bail is swung toward clamping position on one side of the cover.

5. Covering means for cans with cylindrical necks, comprising a sheet-metal cover with a cylindrical rim embracing the can neck and a reinforcing ring on said rim, clamping ears secured to opposite sides of the can in positions outside the cover rim and its reinforcing ring, a bail-formed yoke spanning the cover-reinforcing ring and pivoted thereto, and clamping devices on said yoke, said clamping ears and clamping devices being constructed and arranged to coact to clamp the cover on the can neck when the yoke is swung toward clamping position on one side of the cover.

In testimony whereof I have affixed my signature.

JACOB B. CONOVER.
